UNITED STATES PATENT OFFICE.

JOSEPH T. ROFFY, OF NEW YORK, N. Y., ASSIGNOR TO A K-RAY CORPORATION, A CORPORATION OF NEW YORK.

PROJECTION-LANTERN.

1,159,418.

Specification of Letters Patent.

Patented Nov. 9, 1915.

Application filed January 6, 1913. Serial No. 740,375.

To all whom it may concern:

Be it known that I, JOSEPH T. ROFFY, a subject of the Emperor of Austria-Hungary, and a resident of New York, in the county 5 of New York and State of New York, have made a new and useful Invention in Projection-Lanterns, of which the following is a specification.

This invention relates to improvements in 10 lighting apparatus and more particularly to headlights and searchlights.

An object of this invention has been to provide a headlight or searchlight having two independent beams of light, one of 15 which is achromatic and therefore when properly directed, devoid of glare, and the other of which is of the parallel character. This, as well as other objects which will readily appear to those skilled in this art, I 20 attain in the device described in the specification and illustrated in the single sheet of drawings accompanying the same.

The single figure in the drawings is a dia- 25 grammatic view of a device embodying this invention.

As the housing for the device may be of any desired form or character and does not constitute a portion of this invention, no housing has been shown; merely the ele- 30 ments entering into the makeup of the invention have been shown arranged in proper relation.

The device consists of a parabolic reflec- 35 tor 2 and a spherical reflector 3 so related one to the other that their principal foci coincide. In this common focus the filament 4 of a lamp 5 is placed. The filament is surrounded by a mushroom-shaped globe 6.

Two condensing lenses 7 and 8, which to- 40 gether form a condensing set, are supported along the line of the principal axis of the reflectors and arranged with their plane surfaces toward the light source. Between this lens-set and the light source a ring reflector 9 is placed. This ring reflector is a 45 section of a sphere and is polished on its concave surface and arranged with its prin- cipal focus coinciding with the principal focus of spherical reflector 3.

A projection lens 10 of the convex variety 50 is supported along the line of the common axis of the reflectors and condensing lens-set at a distance from the condensing lens-set which is slightly less than the focus of the projection lens 10. 55

The ring reflector 9 performs a double function; it limits the aperture of the condensing lens-set and recovers deflected light.

It will be seen that with this device two independent beams of light will be pro- 60 jected in a determined and useful direc- 65 tion; one beam which I designate achro- matic will be derived from the condensing set, and one of the parallel character will be derived from the parabola, and both will be projected through lens 10 in the same direction.

Having thus described my invention, what I claim is:

1. In a head light, a source of light, a 70 spherical reflector behind the source of light, a condensing lens in front of the source of light, a parabolic reflector contiguous with the spherical reflector and extending around the lens, a ring shaped spherical reflector 75 between the source and the condensing lens having its concave face next said source and a projecting lens in front of said condens- 80 ing lens and receiving reflected and trans- mitted light from said source. 80

2. In a head light, in combination with a source of light, a spherical reflector behind said source of light, a condensing lens in front of said source of light, the condensing lens and source of light being in close prox- 85 imity, a parabolic reflector surrounding said source of light and a ring shaped inverted reflector between the source of light and the condensing lens, said ring shaped reflector being substantially co-extensive in diameter 90 with the spherical reflector. 85

In testimony whereof, I have hereunto subscribed my name this 2nd day of January, 1913.

JOSEPH T. ROFFY.
